Primary Examiner — Sandra Morris

(74) Attorney, Agent, or Firm — Garvey, Smith, Nehrbass & North, L.L.C.; Brett A. North

(57) CLAIM

The ornamental design for a combined game board and pieces, as shown.

DESCRIPTION

FIG. 1 is a front perspective view;
 FIG. 2 is a front side view;
 FIG. 3 is a rear side view;
 FIG. 4 is a right side view;
 FIG. 5 is a left side view;
 FIG. 6 is a top view; and,
 FIG. 7 is a bottom view.
 The broken line showing of the handles for the game pieces is for illustrative purposes only, and forms no part of the claimed design.
